UNITED STATES PATENT OFFICE

1,986,382

RADIO CIRCUITS

Thomas Douglas Thompson, Little Ferry, N. J.,
assignor to Frank C. Talmadge, New York,
N. Y.

Application May 5, 1931, Serial No. 535,108

5 Claims. (Cl. 179—171)

This invention relates to improvements in multi-stage coupled vacuum tube circuits.

One of the objects of this invention is the provision of improvements in circuit connections for four element vacuum tubes.

- 5 A further object of this invention is the provision of improved circuit connections for four element vacuum tubes having a cathode and anode and a control grid and a space charge grid.
- 10 A further object of this invention involves the connection of such tubes in multi-stage radio and audio frequency stages and detector stages to effect stability of operation.

- 15 A further object of this invention involves connections of such tubes into multi-stage radio circuits so that the circuits may be controlled to produce regeneration and degeneration and stability.

- 20 A still further object of this invention is to couple the space charge grid with the input circuit of the same tube.

- 25 Another object of this invention involves in a multi-stage circuit a coupling between the space charge grid of one tube and the input circuit of another tube.

- 25 These and many other objects as will appear from the following disclosure are secured by means of this invention.

- 30 This invention resides substantially in the construction, combination, arrangement and relative location of parts, all as will be set forth in greater detail hereinafter.

- 35 Figure 1 is the circuit connections of this invention for a radio frequency amplifier, a detector and an audio frequency amplifier connected in cascades;

- 40 Fig. 2 is the circuit connections for a modified form of the invention in which the space charge grid of the detector is coupled to the input circuit of the radio frequency amplifier.

- 45 Fig. 3 is a diagrammatic illustration of another modification of the invention in which the space charge grid of the frequency radio tube is coupled to the input circuit thereof through a capacity.

- 50 The general object of this invention is to provide circuits for four element vacuum tubes of which elements a control grid and a space charge grid are provided. The circuit connections of this invention employing such tubes, are arranged so that regeneration and degeneration and stability may be produced at will.

- 55 The general object also involves the provision of a variable impedance in the space charge grid circuit which is used to control the stability of

the circuit. This impedance, which may be in any of the well known forms, may, likewise, in some forms of the circuit act also as the coupling means by means of which stability of operation is attained.

These objects are attained by means of several forms of circuits which have been illustrated in the drawing.

Referring to Figure 1, the usual grounded antenna circuit with a coupling inductance in it is shown at 1. The coupling inductance of the antenna circuit is coupled to an inductance 2 in the input circuit of the radio frequency amplifier A. One terminal of the inductance tube is connected to the control grid 3 and the other terminal, which is grounded, is connected through a variable resistance 5 to the movable contact of the potentiometer 4 connected across the terminals of the heater for the cathode.

A variable tuning condenser 6 is shunted across the inductance 2. The space charge grid 8 is connected to one terminal of a variable inductance 7 which is coupled to the inductance 2. The other terminal of this inductance 7 is connected through a variable resistance 9 to the positive side of the current source.

The anode 7 is connected through a primary inductance 11 to the positive side of the current source. Coupled to the inductance 11 is the secondary inductance 12, which has one terminal connected through the usual grid lead system to the control grid 14 of the detector tube B. The other terminal of this inductance is connected to the positive side of a current source and to the movable contact of the potentiometer 15 through 35 a small fixed condenser 16. The movable contact is grounded. The potentiometer 15 is connected across the terminals of the cathode heater. The secondary inductance 12 is shunted by the variable condenser 17. The space charge grid 19 is connected to one terminal of the variable inductance 18 which is coupled with the inductance 12. The other terminal of inductance 18 is connected through the variable resistance 20 to the positive side of the current source. The anode 21 is connected through the primary inductance 22 to the positive side of the current source. A secondary inductance 23, coupled with inductance 22, is connected to the control grid 24 of the audio amplifier tube C and to the movable contact of potentiometer 25 through variable resistance 26.

The grid return lead is grounded.

45 The space charge grid 28 is connected to one terminal of the inductance 27 coupled to the pri- 55

mary inductance 22. The other terminal of inductance 27 is connected through variable resistance 29 to the positive side of the current source. The anode 30 is connected through any suitable work circuit to the positive side of the current source.

The cathodes which have been illustrated are the indirectly heated type which may be directly connected to any suitable alternating current source. It is to be understood, however, that this invention may be employed with tubes having any suitable form of cathode, whether directly or indirectly heated and whether supplied with direct or alternating current. The inductances 7, 18 and 27, may be variable and may be movable with respect to the inductances to which they are coupled, to vary the coupling therebetween and to control the phase of the currents flowing in the coupled circuits. With this circuit arrangement, by moving the coils 7 and 18 particularly, the currents flowing therein may be employed to impress voltages on the input circuits to which they are connected to effect regeneration, degeneration or stability.

In the modified arrangement of Fig. 2 only a radio frequency amplifier and a detector stage have been shown. In this case the connections are substantially the same with the exception that the space charge grid 8 of the radio frequency tube A. is connected to the positive side of a current source and the space charge grid 19 of the detector tube B. is connected to one terminal of the variable and adjustable inductance 7 coupled with the input inductance 2.

The circuit arrangement in Fig. 3 is modified in that the space charge grid 8 of the radio frequency tube A. is connected to one terminal of inductance 7 through a variable condenser 41. Inductance 7 is coupled with input inductance 2; an inductance 42 which may be variable is included in the plate circuit.

The space charge grid 19 of the tube B. is connected to the positive side of a current source by wire 40. In these circuits as before, stability of operation may be attained or regeneration or degeneration may be secured. These operations are effected by adjustment of the inductance 7 to vary the phase relation of the voltage impressed upon the inductances to which they are coupled.

I have shown, various forms of impedances in the circuits of the drawing by way of illustration only since I intend it to be within the scope of this invention to use any suitable form of impedance whether variable or fixed, thus, in the drawing I have shown inductances fixed or variable, variable resistances or variable capacities in the space charge grid circuit. It is, of course, within this invention to employ complex impedances made up of any desired combination of resistance, inductance and capacity. As shown in the drawing this impedance may or may not, as desired, be employed as part of the coupling means for interconnecting the circuits as shown and described.

It is of course apparent that this invention is not limited in the number of radio frequency and audio frequency stages which may be employed. The audio frequency output circuit of Fig. 1 and the detector output circuits of Figs. 2 and 3 may be connected to any form of work

circuit without departure from this invention.

This invention residing in certain principles of construction and operation may be embodied in other physical forms than those shown in the drawing and I do not, therefore, desire to be strictly limited to the disclosure as given for purposes of illustration, but rather to the scope of the appended claims.

What I seek to secure by United States Letters Patent is:

1. A circuit combination comprising an audion having a cathode, an anode, a control grid and a space charge grid, an input circuit connected between the cathode and the control grid, an output circuit connected between the cathode and the anode and a stabilizing circuit connected between the output circuit and the space charge grid including a variable impedance coupled to the input circuit for controlling the phase of the voltage impressed on the input circuit to stabilize the operation of the audion and its associated circuits.

2. A circuit combination comprising an audion having a cathode, an anode, a control grid and a space charge grid, an input circuit connected between the cathode and the control grid, an output circuit connected between the cathode and the anode and a stabilizing impedance net work connected to the space charge grid and coupled exteriorly of the audion with the input circuit for impressing an out of phase voltage on the input circuit to suppress oscillation of the audion and its associated circuits.

3. A circuit combination comprising an audion having a cathode, an anode, a control grid and a space charge grid, an input circuit connected between the cathode and the control grid, an output circuit connected between the cathode and the anode, a stabilizing circuit connected to the space charge grid and means for coupling the stabilizing circuit with the input circuit exteriorly of the audion to suppress oscillation of the audion.

4. A circuit combination comprising an audion having a cathode, an anode, a control grid and a space charge grid, an input circuit connected between the cathode and the control grid, an output circuit connected between the cathode and the anode, a stabilizing circuit connected to the space charge grid, and a variable impedance in the stabilizing circuit coupled with the input circuit for controlling the phase of the current flowing therein to stabilize the operation of the audion.

5. A stabilized circuit combination comprising at least two audion tubes each having a cathode, an anode, a control grid and a second grid, an input circuit connected between the cathode and the control grid of each tube, an output circuit connected between the cathode and anode of each tube, the output circuit of the first tube being coupled to the input circuit of the second tube, a stabilizing circuit connected to the second grid of the second tube, and coupled to the input circuit of the first tube, a variable impedance net work forming part of the stabilizing circuit for varying phase of the current flowing therein, the second grid of the first tube having a positive potential impressed thereon.
